UNITED STATES PATENT OFFICE.

JOHN GLENN, OF NEW YORK, N. Y.

REGISTERING DEVICE.

1,064,469.

Specification of Letters Patent. Patented June 10, 1913.

Application filed February 9, 1912. Serial No. 676,510.

To all whom it may concern:

Be it known that I, JOHN GLENN, a citizen of the United States, and a resident of the borough of Manhattan of the city of New York, in the county and State of New York, have invented certain new and useful Improvements in Registering Devices, of which the following is a specification.

The invention relates to registering devices and one of the objects of the invention is to construct a registering device in which a reading may be printed or otherwise formed on a thin strip or sheet of paper and in which the totalizer or other recording means is normally obstructed from view.

Another object of the invention is to construct a cash register with a totalizer normally obstructed from view by means of a movable shutter and also having an inking and printing means normally held in inoperative position. In the preferred construction the movable shutter and the inking and printing means are normally locked and capable of being moved from their normal position only by a removable key adapted to unlock the same.

As showing a specific embodiment of the invention reference is made to the accompanying drawing forming a part of the specification in which,—

Figure 1 represents in perspective the outside view of the top portion of a cash register. Fig. 2 is a partial side view of the registering device, a portion of the operating key and the totalizer, the inking mechanism and the means connecting the inking mechanism and the operating key being indicated by dotted lines. Fig. 3 is a vertical sectional view taken on the line 3—3 of Fig. 4, the means between the inking mechanism and the operating key being indicated by dotted lines. Fig. 4 is a plan view taken on the line 4—4 of Fig. 3 and Fig. 5 is a perspective view of the end members which carry the inking member and the shutter F' which serves as a connecting member between the end members.

A indicates the top of a cash registering device comprising a casing B containing therein the usual operating mechanism provided with the totalizer C. The casing directly above the totalizer is provided with a window or opening c' and a slit or opening c² through which a strip of paper receiving an impression from the totalizer may pass.

An operating key D is pivotally connected

to the casing by means of the shaft d' and this key has slidably mounted therein a shutter E which normally obstructs the totalizer from view through the window c'. This shutter E is held in normal position by the spring e' and may be pushed from said normal position by the key e². There is also carried within the casing an inking and shutter mechanism F having the end members f' thereof slidably mounted in ways f² supported on the casing. The inking of the totalizer is performed by the inking roller F' and the end members f² are connected by the bar or strip F² extending therebetween which serves as a shutter when the mechanism F is in its normal position.

There extends between the operating key, D and the inking and shutter mechanism F the link and lever mechanism G which serves as means to move the inking and shutter mechanism F from its normal position as shown in Fig. 2 to the position shown in Fig. 3 when the operating key is lowered to impress the strip or sheet of paper H, against the totalizer. This link and lever mechanism G comprises the bell crank lever g', the straight lever g², the link g³ extending between the operating key and the bell crank lever, the link g⁴ extending between the bell crank lever and the straight lever g² and the link g⁵ extending between the straight lever g² and an end f' of the inking and shutter mechanism F.

It will be observed from an inspection of Fig. 3 that when the operating key or lever D is depressed from its normal position that the shutter and inking mechanism F will be moved to the right so that the shutter F' and the inking roller F' will respectively be moved away from and across the totalizer.

The operating key D is normally locked and held in its elevated position by means of any suitable locking mechanism comprising a bolt x which can enter the opening d' in the lever. The keyhole for this locking mechanism is indicated by the reference character d² in Fig. 1. The operating key is returned to its normal position from the depressed or printing position by the tension spring d³ clearly shown in Fig. 3.

The opening or slot c² through which a strip of paper may be inserted in order to have printed thereupon a reading of the totalizer is normally closed by one of the end members f' of the inking and shutter means F and as the last mentioned means is nor-

mainly locked, it is apparent that the opening C is normally closed by the end member which is located thereover. The operation is as follows: The operating key D is unlocked by a removable key which is inserted in the keyhole d^2 and the operating key D is partially depressed. This partial movement will cause the inking and shutter means F to travel from its normal position a sufficient amount for the totalizer to be inked and also a sufficient amount for the end member f' to uncover the opening c^2 at the side of the register whereby a strip of paper may be inserted through the opening c^2 into the space between the totalizer C and the movable shutter E on the key. After the strip of paper is thus inserted a further depression of the key will cause the shutter E to impress the paper against the figures on the totalizer or the other indicating characters and thus print upon the paper the reading thereof. Should it be desired to take a reading of the totalizer directly by the eye without printing the same on a piece of paper all that is necessary is to partially depress the key D omit passing the paper through the opening C, and when the key is partially depressed force the shutter E against the compression spring e' by means of the shutter key e^2 thereby removing the only obstruction existing between the totalizer and the window c.

It is obvious that various forms and modifications may be made without departing from the spirit and scope of the invention.

I claim as my invention:

1. A registering device including in combination a totalizer or registering means, movable means and means which normally lock the movable means in inoperative position, the movable means normally obstructing the totalizer or registering means from view, but which when unlocked permits a print or impression to be taken from the totalizer or registering means and which also assists in the formation of the print or impression, said movable means also movable to a position where a reading can be taken directly on the totalizer or registering means.
2. A registering device including in combination a casing provided with registering means, a movable printing and shutter means which normally obstructs the registering means from view and locking means for normally holding the printing and shutter means in inoperative position, the printing and shutter means when unlocked movable so as to impress a reading on a strip of paper or other object, said printing and shutter means also movable when unlocked to such position whereby a reading can be directly made upon the registering means.
3. In a registering device, the combination of a casing, a totalizer, means for normally obstructing the latter from view but

which can be moved so that a reading of the totalizer can be made by the eye of the operator, means for moving the last mentioned means so the totalizer can be read by the eye of the operator, and means for forming an impression or print of the totalizer reading, the last mentioned means being constructed and arranged so that the totalizer can be seen and read when the first mentioned means is in a position for the reading to be made by the eye.

4. A registering device including in combination a casing provided with a window, a registering means within the casing, a movable means normally obstructing the registering means from view through the window, but movable to a position where the registering means can be seen, and printing means co-operatively related with the registering means whereby a reading of the registering means can be impressed, printed or stamped when desired.

5. A registering device including in combination, a casing provided with a window, a totalizer within the casing, a movable shutter normally closing the window but movable to a position where the totalizer can be seen and printing means co-operatively related with the totalizer whereby a reading can be impressed, printed or stamped, the shutter and printing means being constructed and arranged so that the printing means can be brought into operation only after the shutter has been moved from its normal position.

6. A registering device including in combination a casing having a window, a totalizer, a normally locked shutter obstructing the totalizer from view through the window, said shutter being permitted to move from its normal position only by unlocking the same by means of a removable key, and printing means normally locked in inoperative position and movable by the key to operative position only by unlocking by a removable key.

7. A cash register including in combination a casing, a totalizer within the casing, an operating key normally held in elevated position, inking means and means between the operating key and the inking means whereby when the operating key is moved downwardly from elevated position, the inking means will first ink the totalizer and subsequently be moved to a position where an impressing operation can be performed between a member on the key and the totalizer.

8. In a registering device the combination of a casing, a totalizer therein, an operating key provided with a movable shutter normally obstructing the totalizer from view and means co-operatively related with the key whereby when a strip of paper passing through the casing and between the to-

- talizer and the operating key is caused to be impressed by the key against the totalizer a reading of the totalizer will be imparted to the paper.
- 5 9. In a cash registering device, the combination of a totalizer, an operating key having therein a member movable so as to permit the totalizer to be read, an inking means movable between said member and
- 10 the totalizer, means between the operating key and the inking means for moving the inking means when the operating key is moved.
- 15 10. In a cash register the combination of a casing having a window at the top thereof, a totalizer supported within the casing and an operating key having a spring pressed shutter therein normally obstructing the totalizer from view.
- 20 11. A registering device having in combination, a registering means, a shutter for normally obstructing the same from view, means for moving the shutter from the normal obstructing position, means for forming
- 25 a print or impression of the reading of the
- registering means, and means for normally locking the printing or impressing means; the printing or impressing means being constructed and arranged so that a member thereof can be moved whereby the registering means can be read by the eye of the operator at a time when the shutter is moved from its normal obstructing position. 30
12. In a registering device the combination of registering means, movable means 35 for obstructing the same from view, means for moving the same, means for forming an impression or print of the reading of the registering means and means normally locked for preventing the taking of a reading from the registering means by either the operator or the printing means except when the next to the last mentioned means is unlocked.
